UNITED STATES PATENT OFFICE

CHARLES G. JACKSON, OF ST. LOUIS, MISSOURI, ASSIGNOR TO MULTIPLEX FAUCET COMPANY, OF ST. LOUIS, MISSOURI, A CORPORATION OF MISSOURI

DESIGN FOR A BEVERAGE DISPENSING CASING

Application filed December 31, 1931. Serial No. 42,324. Term of patent 14 years.

To all whom it may concern:

Be it known that I, CHARLES G. JACKSON, a citizen of the United States, residing at St. Louis, State of Missouri, have invented a new, original, and ornamental Design for a Beverage Dispensing Casing, of which the following is a specification, reference being had to the accompanying drawing, forming a part hereof.

The figure is a perspective view of a beverage dispensing casing embodying my new design.

I claim:

The ornamental design for a beverage dispensing casing, as shown.

CHARLES G. JACKSON.
